STEAM HAMMER

Eugene C. Clarke, Chambersburg, Pa., assignor to
 Chambersburg Engineering Company, Chambersburg, Pa., a corporation of Pennsylvania

Application January 30, 1934, Serial No. 709,034

3 Claims. (Cl. 121—21)

This invention relates to improvements in steam hammers.

An important object of the invention is the provision of a construction in a steam hammer which will eliminate much of the wastage of motive fluid occurring in hammers as now constructed.

In the steam hammers ordinarily constructed, due to the rapidity of action, it is desirable that reversal of intake and exhaust functions shall take place as rapidly as possible. Such hammers ordinarily incorporate ports at opposite ends of the cylinder for intake and exhaust, which ports are made of the same size, and accordingly will handle equal amounts of pressure fluid and exhaust with the same facility. Quite obviously, a steam hammer, due to the weight of the head, the supporting rod, and the piston, has severe gravity effects to overcome, gravity assisting in the down-stroke, and resisting movement in the up-stroke. An important factor is, of course, to provide as rapid as possible a down-stroke, and due to gravity effects, back pressure is set up unless the ports employed are of relatively large size, and even then noticeable back pressure effects occur. Since the larger the port, the greater the time required for valve movement to open and close the port; and this has resulted in the adoption of medium size ports providing, of course, an excess of pressure fluid inlet on the down-stroke, and an excess of back pressure on such stroke, and an inadequate inlet on the up-stroke.

An important object of this invention is the provision of a port arrangement such that the intake and exhaust on these strokes may be properly proportioned, thereby eliminating back pressure effects, and materially economizing in pressure fluid.

Since such a port arrangement necessarily radically differs from the ordinary port arrangement, and is incapable of control by the usual type of valve, a further object of the invention is the provision of a valve for controlling such port arrangement.

A more specific object of the invention is the provision of a slide valve so constructed that wear is reduced to a minimum, operation of the valve facilitated, and adjustment of the valve to compensate for wear in operation is readily effected.

A further and more specific object of the invention is the provision of a simple and readily producible slide valve structure in which binding of the valve and consequent excessive wear in

operation, together with difficulties in operation, due to unbalanced pressures upon the valve, are completely eliminated.

A further object of the invention is the provision of a slide valve especially adapted for use in conjunction with steam hammers and other constructions wherein it is desirable that the valve be so constructed and mounted that it can move in at least one direction with practically no resistance.

A still further object of the invention is the provision of a valve so constructed that adjustments may be compensated for and the valve inspected to determine the necessity for adjustments of its condition while it is under actual pressure.

These and other objects I attain by the construction shown in the accompanying drawings wherein, for the purpose of illustration, I have shown a preferred embodiment of my invention and wherein:

Fig. 1 is a vertical sectional view through a steam hammer cylinder constructed in accordance with my invention;

Fig. 2 is a section on the line 2—2 of Fig. 1; 25

Fig. 3 is a section on the line 3—3 of Fig. 1;

Fig. 4 is a face view of the valve element;

Fig. 5 is a section on the line 5—5 of Fig. 4;

Fig. 6 is a section on the line 6—6 of Fig. 4;

Fig. 7 is a section on the line 7—7 of Fig. 4; 30

Fig. 8 is a section on the line 8—8 of Fig. 4;

Fig. 9 is a view of one face of the adjustable plate;

Fig. 10 is a side elevation of the plate;

Fig. 11 is a view of the opposite side of the plate; and

Fig. 12 is an enlarged sectional view through the adjusting means.

Referring now more particularly to the drawings, the numeral 10 generally designates a valve chamber at present shown as a portion of the casting 11 of a steam hammer cylinder. The cylinder casting has formed therein upper and lower ducts 12 and 13 for the passage of fluid pressure delivered to the cylinder and exhausted therefrom. The lower passage 13 is relatively large as compared to the passage 12, and at its throat 13a or point of communication with the cylinder is flared so that it may be branched about opposite sides of the cylinder to 50 retain its relative large area. The duct 12 communicates with the valve chamber 10 through relatively restricted port 15; while the duct 13 is branched and communicates with the valve chamber through ports 16 and 17 of the same 55

approximate size as the port 15, and entering the valve chamber at vertically spaced points. In the present instance that wall of the valve chamber through which the ports 15 to 17 enter is illustrated as provided with a wear plate 14 in which the ports are directly formed.

It will be obvious that with the restricted port area during the intake on the down-stroke, a relatively small amount of fluid pressure is admitted to the cylinder, just sufficient to give the hammer the needed impulse and velocity, and that during such down-stroke the relatively wide exhaust passage 13 provided will eliminate any back pressure effects. Conversely, on the up-stroke the passage 13 affords means for admission of a relatively large amount of fluid during a short period, thus giving the initial speed necessary on the up-stroke; while the restricted port 12 provides the necessary cushioning to prevent overrunning of the piston P and consequent damage to the cylinder.

As illustrated, the plate 14 forms one working face of the valve chamber, and the opposite working surface thereof is formed by an adjustable pressure plate designated at 18. This pressure plate has a centrally located port 19 communicating through any suitable throttle valve 20 with a source of motive fluid pressure. The plate 18 has a male joint connection at 21 with a port 22 leading from the throttle valve 20, this connection having about its periphery a seat for packing 23, providing the seal between the plate and the entry port for motive fluid. It will be noted that pressure of the motive fluid will be exerted against the pressure plate to urge the same toward the wear plate 14 through an area equal to the diameter of the joint connection at the periphery of the packing seat, minus the area of the port 19 at the point of communication with the plates between wear and pressure plates 14 and 18. Comparison of these areas may be readily had by an inspection of Fig. 9 in which the periphery of the pressure area at the outer face of the plate appears at 24 and the mouth of the port 19 is indicated in dotted lines.

Between pressure plate 18 and the wall of the chamber 10 are arranged adjusting means generally designated at 25 and engaging the outer face of the plate at points adjacent the upper and lower ends thereof. These adjusting means, as shown in Fig. 12, each comprise a trough-shaped element 26 adapted to engage one of the opposed surfaces, a bar 27 adapted to oppose the other of the surfaces, and shims 28 of desired thickness interposed between the element 26 and bar 27 within the trough. These elements determine the possible recession of plate 18 from plate 14. A further adjusting means 29 similar to the adjusting means 25 is employed to vertically locate plate 18 in the chamber. The plate 14 has formed therein a false port 19a corresponding in size and location to the opening of port 19 through the inner face of plate 18. Plate 18 has false ports 15a, 16a and 17a corresponding in size and location to the ports 15, 16 and 17 of plate 14.

Between the plates 14 and 18, the valve 30 is disposed, this valve comprising a flat-faced body adapted to slidably fit against the faces of the plates 14 and 18 and having formed therein intake and exhaust chambers 31 and 32. In the present type of valve construction, the intake chamber is divided into two sections which are connected by a vertically extending duct 33

formed in the valve body, see Fig. 6. Each of these chambers opens through opposite walls of the valve body through openings of equal area. The exhaust chamber 32 opens through one face of the valve through a port 34, through the sides 5 of the valve, and has communication with a false port 35 of equal area with the port 34 and at the opposite face of the valve from the port 34, through a duct 36. The valve body has additionally formed therethrough ducts 37, 38 and 39, the purpose of which is to establish communication between each port 15, 16 and 17 and its corresponding false port 15a, 16a or 17a. The port 19 is maintained in continual communication with its false port through the upper 15 section of the intake chamber.

With a valve of the type illustrated positioned as shown in Fig. 1, when the valve is elevated, port 15 is placed in communication with port 19, and steam is admitted to the upper end of the 20 cylinders; at the same time the chamber 32 is thrown in communication with port 16, and port 17 has access to the space around the valve from beneath the valve. When the valve is lowered, chamber 31 is thrown into communication 25 with port 16 through its upper section, and the port 17 through its lower section; while port 15 is in communication with the space about the valve from above the valve.

It will be noted that since pressure areas on 30 opposite faces of the valves are equal, and since plates 14 and 18 have corresponding pressure areas through which pressure may be exerted against the valve, the only pressure to which valve 30 will be subjected in operation will be 35 the pressure resulting from adjustment of the plate 18, plate 14 being stationarily secured against the wall of the valve chamber. It will also be noted that the space about the valve designated at 40 is subjected only to exhaust 40 pressures, and since this space extends entirely around the valve, there is no resistance of exhaust pressure to movement of the valve in either direction. Likewise, since only exhaust pressure exists about the valve, there is no necessity for heavily reinforced cover plates, and a light cover plate 41 may be employed which, when removed, will afford access to the valve without the necessity of cutting off the supply of motive fluid, so that the valve may be in- 50 spected in actual operation.

In order that the pressure exerted through plate 18 may be readily regulated and controlled to the setting afforded by the shims 28, the effective area of intake chamber 31 against plate 55 18 is made such that it exceeds the effective area of pressure application through the incoming steam, which tends to urge plate 18 from the plate 14. The steam pressure thus acts to force the plate 18 toward the intake port 22 and 60 seat it firmly against the adjusting means 25. With this arrangement, it is possible to "set up" the valve to such an extent that there will be actual binding in the absence of fluid pressure, and the valve will be freed immediately upon 65 the admission of pressure fluid to such an extent that it will drop by gravity. A valve construction of this character with proper adjustment of the means 25 will at all times operate by gravity on the down-stroke, thus making the construction especially adaptable to use in fluid-pressure-operated hammer constructions by insuring a quick return of the hammer to its raised position following a working stroke.

It has been found that utilizing the construc- 75

tion set forth above results in material advantages in operation of the hammer. Ordinarily, in fluid pressure hammers of the type under discussion, it is necessary to give the dies employed in drop forging a draft of about 7°; that is to say, these dies must be given a 7° taper in order that the die and work may be readily separated. Due to the high speed withdrawal of the hammer with the present construction, and to the high speed of the working stroke it has been possible to reduce this draft from 7° as low as 3° with a resultant material saving both in metal losses and in costs in the reduction of the finished stamping to its ultimate form. In addition to this, it is found that it is possible to use a much smaller cylinder with a consequent saving in fluid pressure, this saving being as high as 30 per cent. Furthermore, it is found that the falling weight of the hammer, that is to say the gravity weight of the hammer, can be materially reduced, the reduction in some instances being approximately 20 percent.

Obviously, certain features of the valve may likewise be employed with equal facility in a number of other forms, as for example, in the slide valve mechanism of a locomotive. Since the valve must necessarily be changed as to its operating structure for adaptation to various types of cylinders, I do not wish to be understood as limiting myself to the particular arrangement herein illustrated except as herein-after claimed.

I claim:

1. In a fluid pressure hammer, a hammer cylinder, a hammer piston operating therein, a hammer rod connected with the piston and extending through one end of the cylinder, a valve chamber, a relatively small port in one wall of said chamber constituting the sole means of communication with the opposite end of the hammer cylinder, a plurality of ports in said chamber wall communicating with the first-named end of the hammer cylinder to simultaneously supply fluid to or exhaust fluid from said end of the hammer cylinder, the last-named

ports being distributed longitudinally of the chamber wall, and valve means in said chamber for controlling said ports.

2. In a fluid pressure hammer, a hammer cylinder, a hammer piston operating therein, a hammer rod connected with the piston and extending through one end of the cylinder, a valve chamber, a relatively small port in one wall of said chamber constituting the sole means of communication with the opposite end of the hammer cylinder, a plurality of ports in said chamber wall communicating with the first-named end of the hammer cylinder to simultaneously supply fluid to or exhaust fluid from said end of the hammer cylinder, the last-named ports being distributed longitudinally of the chamber wall, a valve in said chamber for controlling said ports, said valve permanently covering one of said plurality of ports, and passages in said valve for alternately placing the last-mentioned port in communication with a source of fluid pressure and an exhaust.

3. In a fluid pressure hammer, a hammer cylinder, a hammer piston operating therein, a hammer rod connected to the piston and extending through one end of the hammer cylinder, a valve chamber, a port in said chamber constituting the sole means of communication with the opposite end of the hammer cylinder, a valve movable in the chamber controlling said port for the admission of fluid pressure to and exhaust of fluid pressure from the cylinder, port means in said chamber and communicating with the first-named end of the hammer cylinder, said port means having an effective length in the direction of movement of the valve greater than the corresponding length of the first-named port, said valve being so constructed and arranged that a movement thereof substantially equal to the width of the first-named port renders the entire area of the last-named port means available for supply of fluid pressure to or exhaust of fluid pressure from the first-named end of the cylinder.

EUGENE C. CLARKE. 45
